OP P 15,070

No. 15,070

June 17, 1884

UNITED STATES PATENT OFFICE.

PAUL GROEBER, OF NEW YORK, N. Y.

DESIGN FOR WALL-PAPER.

SPECIFICATION forming part of Design No. 15,070, dated June 17, 1884.

Application filed April 15, 1884. Term of patent 34 years.

To all whom it may concern:

Be it known that I, PAUL GROEBER, a citizen of the United States, residing in the city of New York, county and State of New York, have invented and produced a new and original Design for a Wall or Ceiling Covering, which is especially intended as a wall-hanging or ceiling-filling, of which the following is a specification.

10 The drawing represents a front plan view of the design.

This design is in the Japanese style; and it consists of distinct sets of concentric circles *a*, diverging at equal distances from a common center. The outlines of these circles nearest the axis are undulatory or wave-like, but diminish in this respect gradually until the outside circle is reached, which is a true circle. The shading is varied across part of these circles, giving the appearance of beams of light radiating from the axis. Displayed at irregular distances are circles, squares, leaves, rosettes, &c., *b b*, the interiors of which are ornamented with various devices. One of these 20 circles has three crescents, entwined with a small circle between the points of each crescent. The leaf has a star with six points and

a center. This is surrounded with forty-one small circles or beads. A square has a star for its center, inclosed by a circle, around which is placed a wreath of leaves. The other figures *b b* are variously formed, ornamented, and located.

I claim—

1. The design herein described and shown, consisting of sets of concentric circles overlapping each other, among which are scattered irregularly smaller circles, squares, and variously shaped and ornamented bodies placed eccentrically upon the said overlapping circles.

2. The design herein described and shown, consisting of concentric lines separated from each other by a space substantially their own width, the most central of which lines are of irregular outline, and the outermost one a true circle, and the intermediate lines becoming more and more irregular in outline as they approach the center.

PAUL GROEBER.
